UNITED STATES PATENT OFFICE.

CHARLES DOMINICK, OF BATH, MAINE.

CIGARETTE-CASE.

1,384,690.

Specification of Letters Patent. Patented July 12, 1921.

Application filed April 8, 1920. Serial No. 372,252.

To all whom it may concern:

Be it known that I, CHARLES DOMINICK, a citizen of the United States, residing at Bath, in the county of Sagadahoc and State 5 of Maine, have invented certain new and useful Improvements in Cigarette - Cases, of which the following is a specification.

This invention relates to cases or containers for cigarettes, cigars, and similar articles, and has for one of its objects to provide a simple, convenient and easily manipulated device that will effectually protect the contents, that can be conveniently carried in the pocket, that will facilitate the withdrawal of the articles successively as required without the necessity of opening the container or case, and that will produce a light for the cigarette or cigar.

With these and other objects in view, the 20 invention consists in certain novel features of construction as hereinafter shown and described and then specifically pointed out in the claims, and in the drawings illustrative of the preferred embodiment of the invention.

Figure 1 is a side elevation,

Fig. 2 is a longitudinal sectional elevation,
Fig. 3 is an end elevation.

The improved device comprises essentially 30 a container or casing for the cigarettes or other objects to be dispensed and containing a spring actuated follower acting laterally upon a row of cigarettes therein, an ejector for propelling the foremost articles by an 35 endwise movement, a container for a fuel, and an igniting device operative by the return movement of the ejector to light the fuel.

The casing or container is represented as a whole at 10 and is formed with one side 11 40 removable or preferably hingedly united to the body as at 12.

The interior of the container is divided by partitions 13 and 14 into three compartments, one to contain the ejector and lighting mechanism, one to contain the cigarettes, indicated at 15, and one to provide space in which the ejector is withdrawn when out of action. The larger cigarette containing compartment is provided with an aperture 16 45 next to the partition 13, through which the cigarettes are protruded successively, as hereafter described.

A follower 17 is disposed in the larger compartment, and operated by a spring 17' 50 to force the cigarettes toward the discharge

end, and to maintain the first one constantly in the path of the ejector.

Disposed in the smaller compartment and next to the partition 13, is a receptacle or tank 18 for a suitable fuel, such as gasoline, 60 alcohol, or the like, and formed with a nozzle or wick tube 19 at one end, the latter being arranged opposite to an aperture 20 in the adjacent wall of the casing and through which one end of the cigarette is thrust to 65 light the same, as hereafter explained.

Arranged in the smaller compartment are guide members 21 to slidably receive a bar or rod 22, the latter directed laterally as 70 shown at 23 and thence inwardly toward the larger compartment, and terminates in a laterally enlarged head 24. The head portion 24 is adapted to pass through an opening in the partition 14 in alinement with the opening for the discharge of the cigarettes. 75

The bar 22 and its offset 23 and head 24 constitute the ejector member of the improved device.

Mounted in the smaller compartment and 80 relatively close to the wick tube 19, is a shaft 25 carrying a disk 26 having one element of an igniting compound thereon, and likewise carrying a gear pinion 27 in constant engagement with a gear rack 28 on the bar or rod 22.

Supported within the smaller compartment in the path of the igniting element, on the disk 26 is the other and coacting igniting element 29, the two elements designed to 85 produce a spark when the element 26 is brought in vigorous contact with the element 29, and ignite the fuel escaping through the tube 19, to light the cigarette when thrust through the aperture 20.

Formed in the smaller compartment between the bar 22 and the adjacent end of the case is a relatively long opening 30, and attached to the bar 22 and projecting into the opening is a finger grip element 31.

The member 31 is in the form of a plunger 100 and projects constantly beyond one end of the opening 30 and engages a spring 32 which operates to maintain the plunger and the ejector device connected thereto, yieldably and normally in withdrawn or inoperative position, and also to return the ejector with a very quick movement to inoperative position when released, to insure the effectual action of the igniting elements of the device. 105

When the person carrying the device de- 110

sires a cigarette, he inserts the forefinger in the opening 30 and exerts pressure upon the plunger 31 and thus moves the bar 22 endwise in the guides 21 and likewise forces the 5 head 24 against the inner end of the first or outermost cigarette and forces its outer end through the opening 16 into position to be fully withdrawn from the case or container.

- 10 This movement of the plunger causes the rack 28 to rotate the shaft 25 in one direction. The finger is then withdrawn from the aperture 30 permitting the spring 32 in its reactive movement to very quickly 15 return the bar 22 to normal position and correspondingly and quickly rotate the ignition element of the member 26 against the element 29 and produce a spark to ignite the fuel escaping from the tube 19, and thus 20 produce a slight flame with which the tip of the cigarette can be engaged when thrust through the aperture 20.

The user of the device can then easily extinguish the light by blowing through the 25 opening 20.

The device is simple in construction, can be inexpensively manufactured of any suitable material or in any required size or capacity.

30 The preferred embodiment of the invention is disclosed in the drawings and set forth in the specifications, but it will be understood that any modifications within the scope of the claims may be made in the 35 construction without departing from the principle of the invention or sacrificing any of its advantages.

I claim:

1. In a device of the class described, a 40 container for the articles to be dispensed and having a discharge opening, a receptacle

for fuel having a lighting orifice, an ejector coacting with the opening, means for actuating the ejector, means for lighting the fuel at the orifice, and means whereby the return 45 movement of the ejector actuates the fuel lighting means.

2. In a device of the class described, a container for the articles to be dispensed and having a discharge opening, a receptacle 50 for fuel having a lighting orifice, an ejector coacting with the opening, a trigger device movable upon the container and connected to the ejector, means connected to the ejector for lighting the fuel at the orifice, and means 55 whereby the return movement of the trigger and ejector actuates the fuel lighting means.

3. In a device of the class described, a container for the articles to be dispensed and having a discharge opening, a receptacle 60 for fuel having a lighting orifice, an ejector coacting with the opening, means for actuating the ejector, a rotative member adapted for lighting the fuel at the orifice, and means 65 whereby the return movement of the ejector actuates the rotative fuel lighting means.

4. In a device of the class described, a container for the articles to be dispensed and having a discharge opening, a receptacle for 70 fuel having a lighting orifice, an ejector coacting with the opening, a shaft carrying a fire producing medium and a pinion, a rack carried by said ejector and engaging said pinion, means for moving the ejector in one direction, and a spring arranged to return 75 the ejector to initial position and to reverse the movement of the shaft carrying the fire producing medium and effect the ignition of the fuel at the orifice.

In testimony whereof, I affix my signature hereto.

CHARLES DOMINICK.
